UNITED STATES PATENT OFFICE

2,517,095

ILLUMINATED SIGN WITH EDGE-
ILLUMINATED LETTERS

Ramon V. Dixon, Detroit, Mich., assignor to General Motors Corporation, Detroit, Mich., a corporation of Delaware

Application April 3, 1947, Serial No. 739,096

9 Claims. (Cl. 40—130)

1

This invention relates to an illuminated sign or display device.

An object of the invention is to increase the efficiency of a sign of this general character and to produce the visual effect of edge illumination without employing the normally fragile transparent materials employed in edge-illuminated signs.

An object of the invention is to produce a sign embodying three-dimensional letters with the edges brightly illuminated and the faces dimly illuminated.

An object of the invention is to provide a durable sign of simple and economical construction wherein the parts are conveniently arranged for maintenance.

Other objects and advantages of the invention will be apparent from following the specification in conjunction with the accompanying drawing.

In the drawing:

Figure 1 is an elevation view of an illuminated sign embodying the invention.

Figure 2 is an enlarged cross-section on the line 2—2 of Figure 1.

Figure 3 is an enlarged fragmentary detail in perspective of the three-dimensional letters mounted on the panel.

Figure 4 is an enlarged and exploded fragmentary detail in perspective of the letters on the light shield.

Though edge-illuminated signs have many desirable features, such as high daylight visibility, they are fragile due to necessary employment of a transparent material, and they are expensive because the light source must be mounted along the edge of the transparent material. This expense is increased where the illuminated edge is not straight. The sign made in accordance with this invention produces the visual effect of edge illumination, but does not employ fragile materials, and employs a conventional light source.

The preferred embodiment illustrated in the drawing consists of an elliptical panel 10 of suitable material, such as wood, metal or fiberboard. The general outline of panel 10 may be shaped to simulate the user's trade-mark or other pictorial shape. The perimeter of the panel 10 is framed with a moulding 11 mounted on the front side of the panel. The inner edge of the moulding 11 is perpendicular to the panel 10 and has reflecting surface 12. The moulding 11 may be formed of chrome-plated sheet-metal U-shaped in cross section, as shown in Figure 2, with tabs 13 for suitably securing the moulding to the

2

panel, and a flange 31 to provide a finished inside edge.

The light source is provided by an elongated bulb or preferably a fluorescent light tube 14 positioned at the front of the panel 10 with its center line in the plane of the outer edge of the moulding or just outside of said plane and mounted in conventional sockets 15, one at each end of the tube 14. The sockets 15 extend through an aperture in panel 10 and are secured to the rear face of the panel 10. The secured portion of the sockets 15, the electrical connections and the usual transformer are housed in the electrical outlet box 16 secured to the rear face of panel 10. Suitable means, such as cord 17, provides the electrical connection for the light tube.

The light tube 14 is shielded from direct vision by the light shield 18 made of opaque material and mounted by supports 19 on the front panel 10. A support 19 is employed adjacent each end of the light tube 14 and is preferably mounted just inside each bracket 15. Each bracket 19 is formed of a thin strip of spring metal of U shape with the base secured to the front of panel 10 and the ends of each leg bent outwardly to form a hook 20. These hooks 20 engage suitable latch cleat elements secured to the rear face of shield 18 to support the shield detachably on the panel. The shield 18 may be removed to replace the light tube 14 merely by squeezing the legs of supports 19 to disengage the hooks 20 from latch cleats 21.

The indicia comprising the main lettering of the sign is formed of three-dimensional letters 22 with a pronounced bevel 23 on all edges as shown in Figure 3. The letters are formed with the bevel 23 providing a light-reflecting surface in white or a light-color shade, while the face 24 of the letters has less reflecting capacity and is a darker shade of color. The letters 22 are preferably moulded of ceramic material with a highly glazed white surface on the bevel 23 and a dark-colored glaze, such as blue or black, on the face 24. The panel is painted a contrasting color such as orange, to provide a contrast to the color employed on the face of the letters.

The light from the tube 14 illuminates the adjacent beveled edges of the letters 22 directly, and the remote beveled edges by reflection from surface 12 of the molding. The reflecting surface 12 of the moulding 11 is positioned substantially perpendicular to the panel 10 best to reflect light on the bevel edges 23 remote from the light. The combination of direct lighting and the reflected lighting at the edges of the panel 10 also

3

provides substantially uniform illumination on this panel. The visual appearance of the letters, consisting of the illuminated dark face of the letters surrounded by the highly illuminated white bevel, is similar to edge-illuminated letters cut in transparent material and has the same high degree of visibility.

The light shield 18 may be shaped to provide a pictorial representation as a part of the user's trade-mark or his product. To provide additional indicia, such as letters 25 or design portion 30, parts may be cut out of the light shield and a sheet of transparent plastic material 26 secured over the entire surface of the light shield. The letters on the transparent sheet 26 may consist of transparent, light-colored or white outline portion 27 and a darker and partially transparent portion 28, to produce a visual effect similar to the three-dimensional letters 22. As a modified form of lettering, the portion of the sheet around the letters may be colored and opaque if it is desired to avoid the accurate cutting out of the letters in light shield 18. Support means, such as hooks or a wire stand 29, may be employed to position the sign suitable for display.

This preferred embodiment of a sign made in accordance with the invention is merely illustrative of the generic inventive concept presented in the present application and defined in the claims. Thus numerous modifications and embodiments within the scope of the appended claims will be apparent to those skilled in the art.

I claim:

1. An illuminated sign, consisting of a panel, a moulding positioned along an edge of said panel and projecting forwardly of said panel, the inside face of said moulding having a reflecting surface, a light source substantially centrally located on said panel, a light shield positioned in front of said light source, means attached to said panel and supporting said light shield, indicia consisting of three-dimensional letters having pronounced beveled edges and a flat front face positioned on the panel between the light source and the moulding reflecting surface, said light source having a center of light emanation spaced from said panel slightly further than the face of said letters whereby the panel is uniformly illuminated directly and by reflection and the beveled edges of the letters are brightly illuminated directly on the side adjacent the light and by reflection on the side adjacent the moulding while the faces of the letters are dimly illuminated.

2. An illuminated sign as defined in claim 1, in which said three-dimensional letters are of moulded ceramic material, the beveled edges being coated with a white glaze and the face being coated with a lark-colored glaze.

3. An illuminated sign as defined in claim 1 in which said moulding is a strip of sheet-metal formed to a U-shaped cross section the outer leg of said U-shaped section being extended and secured to the edge of said panel, and the reflecting surface consists of a metallic plating and is positioned substantially perpendicular to the panel.

4

4. An illuminated sign as defined in claim 1, in which said shield support means consists of a U-shaped strip of spring metal with the base thereof secured to the panel and having resilient legs extending outwardly from said panel, the ends of the legs of the U shape are oppositely bent to provide allochiral hooks, latch allochiral cleats secured to said shield, said hooks engaging in said latch cleats to support said shield on the panel to shield said light source from direct vision.

5. An illuminated sign as defined in claim 1, in which said light shield is cut out to provide additional indicia, and a sheet of transparent plastic material covering said cut-outs.

6. An illuminated sign as defined in claim 1, in which said light source is located substantially in the plane of the front edge of said reflecting surface.

7. An illuminated sign as defined in claim 1, in which said reflecting strip on the moulding is perpendicular to said panel and extends outwardly to the center line of said light source and said three-dimensional letters are of moulded ceramic material, the beveled edges being coated with a white glaze and the face being coated with a dark glaze.

8. An illuminated sign as defined in claim 1, in which said three-dimensional letters have light-colored, light-reflecting beveled edges and dark-colored light-absorbing face surfaces.

9. An illuminated sign, consisting of a panel, a light source located substantially centrally on said panel, a light shield positioned in front of said light source to shield the light from direct vision, reflecting means positioned along an edge of said panel to reflect light to the panel, beveled three-dimensional letters positioned in said panel between the light and said reflecting means, said light source having a center of light emanation spaced from the panel surface slightly more than the thickness of said letters whereby the panel is uniformly illuminated and the bevel on the letters is brightly illuminated on the near side directly and on the far side by reflection while the face of the letters is dimly illuminated.
